CLAIM

The ornamental design for a handbag, as shown and described.

DESCRIPTION

1. Handbag

1.1 : Perspective

1.2 : Front

1.3 : Back

1.4 : Right

1.5 : Left

1.6 : Top

1.7 : Bottom

1.8 : Perspective

In the drawings dashed lines represent stitching which form no part of the design and are not claimed, and parallel thinner lines represent shadings and do not illustrate ornaments or decorations; reproduction 1.8 shows the handbag with open clasp.

1 Claim, 8 Drawing Sheets(56)
